BURNER

La Clede Lientz, Prairie Village, and Robert S. Harber,
Overland Park, Kans., assignors to Lientz Manufacturing,
Inc., Kansas City, Mo., a corporation of
Missouri

Filed Jan. 11, 1965, Ser. No. 83,382

Term of patent 14 years

(Cl. D81—1)

Fig. 1.

Fig. 2.

Fig. 3.

Fig. 4.

FIG. 1 is a top plan view of a burner, embodying our new design;

FIG. 2 is a front elevational view of same;

FIG. 3 is a side elevational view of same taken from the left-hand side of FIG. 2;

FIG. 4 is a rear perspective view of same showing the side opposite that shown in FIG. 3.

The essential features of our design reside in the portions shown in solid lines.

We claim:

The ornamental design for a burner, as shown and described.
